UNITED STATES PATENT OFFICE.

WILLIAM I. BUNKER, OF LA GRANGE, ILLINOIS.

DESIGN FOR A SADDLE-CUSHION.

SPECIFICATION forming part of Design No. 28,337, dated March 1, 1898.

Application filed December 11, 1897. Serial No. 661,566. Term of patent 14 years.

To all whom it may concern:

Be it known that I, WILLIAM I. BUNKER, a citizen of the United States, residing at La Grange, Cook county, Illinois, have invented and produced a new and original Design for a Saddle-Cushion, of which the following is a specification.

In the accompanying drawings, Figure 1 is a plan view showing one side of a saddle-cushion illustrating my design; Fig. 2, a similar view showing the reverse side thereof, and Fig. 3 a cross-section taken on line 3 of Fig. 1.

The leading feature of my design consists in a body A, having a narrow front or pom-

mel portion B and a broad rear or seat portion C, and having cellular work throughout substantially its entire area, the seat portion having a slit or opening D, extending therein from the rear, the whole presenting an ornate and attractive appearance, as shown in the drawings.

I claim—

The design for a saddle-cushion substantially as shown and described.

WILLIAM I. BUNKER.
